UNITED STATES PATENT OFFICE

HERBERT LEONARD PLUMMER AND DAVIS LAMBERT IRWIN, OF HIGH HOLBORN,
LONDON, ENGLAND

CONSTRUCTION OF ROOFINGS, PARTITIONS, AND THE LIKE

Application filed May 31, 1930, Serial No. 458,618, and in Great Britain September 5, 1929.

This invention relates to the construction of roofings, partitions and the like and the main object of the invention is to provide metal sheets or panels, adapted to be secured 5 to the purlins of the roof or to battens or to corresponding members in the construction of partitions, walls or the like having a substantially flat surface which may thereafter be treated as, for instance, by the application 10 thereto of bituminized felt or of flexible roofing material in sheet form.

The invention consists, broadly, in a substantially flat sheet or panel provided on each 15 of two of its opposite sides with a flange whereby it may be interlocked or interchanged with similar sheets and with reinforcing ribs generally parallel with the said flanges extending beyond one edge of the sheet or panel adapted to interengage with 20 the reinforcing ribs on a similarly formed adjacent sheet or panel.

Thus in accordance with the invention the main portion of the sheet may be substantially flat with a plain flange on one of its 25 sides the surface of which extends at right angles with the main portion of the sheet or panel and a flange on the opposite side of the sheet or panel arranged with an upturned edge forming a recess in which the plain 30 flange of an adjacent sheet or panel may be engaged and a plurality of reinforcing ribs extending the length of the sheet or panel parallel with the flanges and projecting beyond one end of the sheet or panel to form 35 projections adapted to engage the reinforcing ribs of an adjacent sheet or panel.

Conveniently, the reinforcing ribs are in the form of channel members of sheet metal secured, for instance, to the body of the sheet 40 or panel by welding or other suitable method of connection, the adjacent ends of the channel members extending beyond one edge of the sheet or panel to provide means for connecting the said sheet or panel with the ribs 45 on an adjacent sheet or panel.

The reinforcing ribs will be so formed as to provide a spigot and socket joint, and to this end the portions of the ribs projecting beyond the edge of the sheet or panel may be 50 either relatively smaller or relatively larger

in effective cross section than the portions of the ribs adapted to engage such projections.

Thus the ends of the ribs which are substantially flush with one edge of the sheet or panel may be expanded suitably in order that 55 in them may be engaged the ends of the ribs extending beyond the edge of an adjacent sheet or panel.

Alternatively the projecting portions of the ribs may be expanded suitably in order 60 that in them may be engaged the ends of the ribs substantially flush with one edge of an adjacent sheet or panel.

Conveniently, the reinforcing ribs, when of channel section, are flanged for the greater 65 portion of their length to assist in securing connection between them and the main portion of the sheet or panel.

Preferably, the reinforcing ribs at points adjacent to the edge of the sheet or panel 70 with which the ends of the ribs are flush are provided with holes through which hook-bolts, screws, or the like may be passed for the purpose of securing the sheet to a purlin or like structural member and to facilitate 75 securing the sheet or panel in position, holes may be provided in the material of the sheet or panel through which a screw-driver, box-spanner or the like may be introduced to facilitate fastening the sheets or panels in 80 position.

Normally the depth of the ribs and of the flanges on the sheets or panels will be equal.

The invention also extends to roofings, partitions, walls and like constructions including a flat sheet or panel as defined above. 85

When material in accordance with the invention is employed in the construction of roofing a plurality of sheets formed as above described are laid up in position on the roof 90 purlins and secured thereto by hook-bolts, screws, nails, or the like passed through the holes provided in the reinforcing ribs after which the external surface of the roof so formed is treated in order to render the same 95 impermeable to water.

Thus, for instance, to the surface of the sheets may be applied flexible roofing material such as bituminized felt.

In some cases it may be found convenient 100

to form the reinforcing ribs integral with the main portion of the sheet or panel but generally it may be stated that it is more convenient and cheaper to form the ribs separately from the main portion of the sheet or panel by, for instance, pressing them from sheet material and subsequently securing the ribs thus formed to the main portion of the sheet or panel by a welding operation.

10 The invention will be described further in detail and by way of example with reference to the accompanying drawings in which:—

15 Figure 1 is a plan view illustrating the construction of a sheet or panel in accordance with the invention.

Figure 2 is a sectional elevation taken along the line II, II of Figure 1,

20 Figures 3 is a sectional elevation taken along the line III, III of Figure 1,

Figure 4 is a fragmentary view partly in section illustrating the application of sheets or panels as illustrated in Figures 1 to 3 to the construction of a roof,

25 Figure 5 is a detailed view illustrating a convenient treatment of the ridge in a roof construction of the kind illustrated in Figure 4,

30 Figure 6 illustrates the method of cleating insulating material to the sheets in forming a roof,

Figure 7 is a sectional elevation along the line VII, VII of Figure 6,

35 Figure 8 illustrates details of surface treatment at a trough or valley formed by the junction of two sloping roof surfaces,

40 Figure 9 illustrates details of surface treatment at a trough or valley formed by the junction with a wall of a roofing construction of the kind illustrated in Figure 4,

Figure 10 is a detailed view illustrating a ridge in a construction of roof of the saw-tooth type, while

45 Figure 11 illustrates a method of treatment for the edge of a roof construction.

In the drawings 1 indicates a substantially flat sheet or panel having on one of its sides a plain flange 2, the surface of which extends at right angles with the main portion of the sheet or panel, and a flange 3 on the opposite side of the sheet arranged with an up-turned edge forming a recess 4, in which the plain flange 2 of an adjacent sheet or panel may be engaged, and lengthwise of the sheet or panel parallel with the flanges, is provided a plurality of reinforcing ribs 5, the ends of which at one end of the sheet or panel project beyond the edge of the latter to form projections 6 adapted to engage the ends 7 of the reinforcing ribs of an adjacent sheet or panel.

The reinforcing ribs 5 are in the form of channel members of sheet metal secured to the body of the sheet or panel by welding or other suitable method of connection, and 65 are also formed so as to provide a spigot-

and-socket joint between ends of adjacent sheets or panels, and to this end the projecting portions 6 are formed relatively smaller in effective cross-section than the portions 7 of the ribs of an adjacent sheet which they are adapted to engage, and the ends 7 of the ribs are also extended for the same purpose.

70 In order to assist in securing connection between the reinforcing ribs 5 and the main portion of the sheet or panel, flanges 8 are provided on the ribs adapted to be welded, soldered, or connected in any other suitable manner to the sheet or panel, and the ribs are provided in the portions 7, see Figures 1 to 4, with holes 9, and in the projections 6 with holes 10 through which hook-bolts 11 or other suitable fastening means may be passed for the purpose of securing the sheet or panel in position and for interlocking the projections 6 of one sheet with the extended portions 7 of an adjacent sheet.

75 In a roof construction in accordance with the invention, see Figures 4 to 11, a plurality of sheets or panels formed as above described are laid in position on purlins 12 with the flanges 2 of the sheets engaging the recesses 4 of adjacent laterally disposed sheets, and the projections 6 of the sheets engaging within the portions 7 of adjacent longitudinally disposed sheets, and are secured to the purlins, see Figures 4, 5, 6, 7 and 11, by means of hook-bolts 11.

80 To the surface so formed is applied a layer of insulating material 13 and a layer or a plurality of layers 14 of bituminized felt or like flexible roofing material, the insulating material being secured in position on the sheets, see Figures 6 and 7, by means of cleats 15 engaging therewith and secured to the hook-bolts 11, the points of the cleats being hammered down level with the surface of the insulating material.

85 In the treatment of the ridge of a roof as illustrated in Figure 5, a ridge plate 16 is located on and extends over the edges of the adjacent sheets and a strip of flexible roofing material 17 is arranged, as shown, to provide a weather proof sealing at the edge of the ridge.

90 In the trough or valley construction illustrated in Figure 8, the sheets or panels are secured to the purlins adjacent to the edges thereof by means of the bolts 18, which bolts also serve to secure in position the valley cover strip 19 upon which is disposed a light 95 concrete filling 20; the insulating material and the flexible roofing material being continued unobstructed over both roof surfaces and the surface of the filling.

100 In a trough or valley treatment at the junction with a wall of a roof surface as shown in Figure 9, the layer of insulating material is continued to the wall surface, a filling of light concrete 21 is laid thereon 105 in the trough or valley, and the layer of 110

flexible roof material is continued from the roof surface over the surface of the filling and for a suitable distance over the surface of the wall, that part of the flexible roof material on the wall surface being reinforced by means of flashing 22 composed of flexible roofing material secured in position by means of lead wedges or any other suitable means.

10 In the treatment of the ridge of a roof of the so-called saw-tooth type, illustrated by Figure 10, a zinc closer 23 is laid along the ridge; and secured to the purlin 24 by means of the fixing strip 25 is the lead flashing 26 adjacent to which is located the glazing 27.

15 A closure for the edge of the roof is formed, see Figure 11, by means of the zinc sheet 28 covering both the edge of the roof and the portions thereof on the upper and lower surfaces adjacent to the edge, and the closure is secured in position by means of the bolt 29, the head of which is formed flush with the surface of the zinc on the upper side of the roof; that part of the zinc sheet covering the upper surface, being located between the layer of insulating material and the surfaces of the sheets or panels adjacent to the edge of the roof.

20 30 The invention provides a flat, non-combustible and economical construction of roof to which flexible roofing material may be applied and while the main utility of the invention is perhaps to be found in the construction of roofs it will be understood that sheets or panels in accordance with the invention may be laid up to form a vertical or inclined structural member other than a roof such, for instance, as partitions, party walls, or the main walls of sheds, garages and like structures.

25 We claim:

1. A substantially flat panel of rectangular form adapted for use on structural surfaces comprising flanges whereby the sides of the panel may be interengaged with the sides of adjacent similarly formed panels, reinforcing ribs generally parallel with the said flanges extending beyond one edge of the panel, and apertures in the said ribs adapted to accommodate a fastening member for securing the panel to a structural member.

2. A substantially flat panel of rectangular form adapted for use on structural surfaces comprising flanges whereby the sides of the panel may be interengaged with the sides of adjacent similarly formed panels, reinforcing ribs generally parallel with the said flanges extending beyond one edge of the panel, apertures in the said ribs adapted to accommodate a fastening member for securing the panel to a structural member, and further apertures in the material of the panel above the apertures in the ribs adapt-

ed to facilitate access to the fastening member and adjustment thereof by a suitable tool.

In testimony whereof we have signed our names to this specification.

70 HERBERT LEONARD PLUMMER.
DAVIS LAMBERT IRWIN.
